[57] CLAIM

The ornamental design for a diamond necklace, substantially as shown and described.

DESCRIPTION

FIG. 1 is a top plan view of a diamond necklace showing my new design portions of the continuous neck chain being broken away for convenience of illustration;

FIG. 2 is a bottom plan view thereof;

FIG. 3 is a side elevational view thereof; and

FIG. 4 is a sectional view as seen from the plane 4—4 in FIG. 3.

FIG. 1.

FIG. 2.

FIG. 3.

FIG. 4.
